(57) **CLAIM**

The ornamental design for a glitter pencil having two color glitters with swirl effect, substantially as shown and described.

DESCRIPTION

FIG. 1 is a side elevational view of a glitter pencil having two color glitters with swirl effect showing my new design; FIG. 2 is a front elevational view thereof;

FIG. 3 is a bottom plan view thereof;

FIG. 4 is a top plan view thereof; and,

FIG. 5 is an enlarged fragmentary view of the junction of the two lower sections.

The structure depicted by means of broken lines has been shown for illustrative purposes only and forms no part of the claimed design.
